UNITED STATES PATENT OFFICE.

JACOB STRAUS, OF ST. LOUIS, MISSOURI.

HORSE-COLLAR FASTENING.

SPECIFICATION forming part of Letters Patent No. 423,350, dated March 11, 1890.

Application filed November 14, 1889. Serial No. 330,306. (No model.)

To all whom it may concern:

Be it known that I, JACOB STRAUS, of the city of St. Louis, in the State of Missouri, have invented a certain new and useful Improvement 5 in Horse-Collar Fasteners, of which the following is a full, clear, and exact description, reference being had to the accompanying drawings, forming part of this specification.

10 My invention relates to an improved device for attaching or fastening together the ends of a separable horse-collar; and my invention consists in features of novelty hereinafter fully described, and pointed out in the claim.

15 Figure I is a detail view showing the lower ends of a separable horse-collar with my improvement applied. Fig. II is a longitudinal section taken on line II II, Fig. I. Fig. III is a view showing the fastening detached and 20 the ends of the collar slightly apart. Fig. IV is a transverse section taken on line IV IV, Fig. I, and looking in the direction of the arrow.

25 Referring to the drawings, A B represent the lower ends of a separable horse-collar.

1 represents one member or casting of the fastening secured to the part B of the collar, and 2 the other member or casting of the fastening secured to the part A of the collar. I 30 make no claim as inventor to the manner of securing these members of the fastening to the collar, and they may be secured in any desirable manner.

The member 2 is provided with a projection 35 3, which fits in a perforation 4 in the member 1, and the member 1 is preferably

mortised out, forming shoulders 5 on the same plane and at an angle to each other, against which the outer end 6 and the upper edge 7 of the member 2 bear to prevent movement 40 of the parts when attached. To insert the projection 3 into the perforation or socket 4, the end B of the collar is moved slightly inward beyond the member A, and then being brought back into line with the member A 45 the insertion is made. When the collar is in use, the strain is thus taken by the projection 3, which is held in the perforation 4 by means of a latch 8, pivoted at 9 to the member 2, and which is provided with a slot 10 to receive a 50 lip 11 on the member 1, as shown in Figs. I and II. This latch prevents inward or outward movement of the parts A B relatively to each other, and thus holds the projection 3 in the perforation 4, as shown in Figs. II 55 and IV.

A fastening thus constructed is strong and durable, is not liable to get out of order, and the attachment can be easily and quickly made.

60 I claim as my invention—

In a collar-fastener, the combination of the member 1, provided with a perforation 4, and the member 2, provided with a projection 3, and latch 8, pivoted to the member 2 and 65 having a slot to receive a lip 11 on the member 1, substantially as and for the purpose set forth.

JACOB STRAUS.

In presence of—

GEO. H. KNIGHT,
E. S. KNIGHT.
